UNITED STATES PATENT OFFICE

DANIEL HANDELAN, OF MINNEAPOLIS, MINNESOTA

HUMIDIFYING DEVICE

Application filed January 22, 1927. Serial No. 162,916.

My invention relates to humidifying devices and has for an object the provision of a device which will purify and maintain the air in rooms of buildings in a moistened condition.

Another object of the invention resides in providing a case having upper and lower openings, together with a spray nozzle situated adjacent said upper opening for directing a spray of water downwardly along said case, and a drain at the lower portion thereof for removing the surplus water from said case.

A still further object resides in providing a removable partition within the lower portion of said case, said partition being removable through the lower opening, and being adapted to form a reversed constricted passageway at the lower portion of said case communicating with said lower opening.

Another object of the invention resides in providing a curved deflector attached to the interior of the case immediately above said opening and communicating with said partition, and in further providing a second deflector secured to said partition in spaced relation thereto, and removable with said partition through said lower opening.

Other objects of the invention reside in the novel combination and arrangement of parts and in the details of construction hereinafter described and claimed.

In the drawings illustrating an embodiment of my invention,

Fig. 1 is an elevational view showing the device installed in the wall of a building.

Fig. 2 is a vertical sectional view taken on line 2—2 of Fig. 1 and drawn to a somewhat enlarged scale.

Fig. 3 is a perspective view of the removable partition of the invention.

Fig. 4 is an enlarged fragmentary detail view of a corner of the register frame.

Fig. 5 is a sectional view taken on line 5—5 of Fig. 4.

The invention proper consists of an elongated rectangular sheet metal case A comprising side walls 9 and 10 and front and rear walls 11 and 12. The front wall 11 is provided at its upper end with a register open-

ing 13 and near its lower end with a second register opening 14, said openings being surrounded by flanges 16 and 17. The upper portion 15 of the rear wall 12 is curved towards wall 11 while at the lower end of the case is provided a trough-like casting which forms a suitable bottom for the device.

Within the interior of the case is provided a water supply pipe 19 connected to a water supply line 21 which pipe terminates in a downwardly directed spray nozzle 20 situated near the upper end of said case. A cock 22 in the pipe 19 regulates the amount of water delivered to the humidifying device while a drain 23 formed in the casting 18 and provided with an overflow pipe 25 connected to a suitable waste pipe 24, serves to conduct away the surplus water.

Within the lowermost portion of case A is placed a vertical partition 26 which extends between the walls 9 and 10 and is spaced from the two walls 11 and 12. This partition is insertible through the register opening 14 and is movable along two flanges or guides 27 secured to the walls 9 and 10. These flanges are turned up at their lower ends, as indicated at 127, to form stops or rests for supporting the lower edge of the partition 26, which is disposed in spaced relation to the bottom 18 of the device. Adjacent the upper end of the register opening 14 I provide a curved deflector 28 which extends between the walls 9 and 10 and which is attached to the upper portion of flange 17. This deflector extends over to the upper portion of the partition 26, and in conjunction with said partition forms a reversed constricted passageway 31 by means of which the moisture laden air entering the upper portion 30 of the humidifier through the register opening 13 may be discharged through the register opening 14. An opening 29 in this deflector permits of attaching a suitable key to the cock 22 in pipe 19 so that the supply of water may be regulated at will.

In the operation of the device the downwardly directed spray of water from the nozzle 20 causes the air to enter the register opening 13 and pass downwardly through the upper portion 30 of case A at the same

time causing washing and humidifying of the same. As the current of air enters the constricted passageway 31 its velocity increases and when it strikes the curved portion 18 is 5 reversed in direction causing a certain portion of the larger globules of water suspended within the air to be precipitated and deposited in this trough-like casting where the same may drain from the device through the drain 10 23. The air on passing upwardly strikes the curved deflector 28 and is discharged through the register opening 14, which causes the further precipitation of the large globules of moisture from the air. In addition to deflector 28 a second deflector 32 is employed which is disposed in spaced relation to the partition 26 and extends in the same general direction as said partition and the deflector 28, terminating at a point intermediate the upper and 15 lower edge of the register opening 14. This second deflector is preferably attached to two wing-like portions 33 and 34 formed on the upper part of the partition 26 and is removable from the device through the register 20 openings 14 with said partition.

The registers used with my invention which I have indicated at B, are preferably constructed as illustrated in Figs. 4 and 5. These registers are formed with a frame 35 30 of U-shaped cross section, Fig. 5, provided with inwardly turned flanges 36 and 37. Flange 36 is provided with notches 38 spaced at suitable intervals throughout its extent so as to receive cords 39 which may be placed 35 across the same, to provide an ornamental facing for the register. The frames 35 of registers B are adapted to slide in U-shaped register casings 40 and 41 attached to the flanges 16 and 17 of register openings 13 and 40 14, which register casings are open along the upper portions of the same to permit of the insertion or removal of said registers therefrom. By means of this arrangement access is had to the interior of the humidifier so that 45 the water supply may be readily turned off or on and so that the nozzle and the drain may be cleaned or repaired when the occasion arises. Access to the drain 23 is further accommodated by the removal of the partition 50 26 through the register opening 14.

The case A, as constructed, is adapted to be arranged between the studding 51 and plastering 52 of the walls of an ordinary frame building, as illustrated in Figs. 1 and 2. 55 The flanges 16 and 17 extend through the plastering 52 to permit the attachment of the registers B to the face of the wall so as to be readily removed.

My invention is particularly advantageous 60 in that it provides a simple and effective device for furnishing properly washed and humidified air to the rooms of buildings. The device may be practically concealed within the walls of the building. By means of 65 the removable registers and partition, access

may be readily had to the various parts of the invention permitting the same to be cleaned or repaired. By means of the reversed constricted passageway and the curved deflectors, the larger particles of water in the 70 moisture laden air are effectively removed.

Changes in the specific form of my invention, as herein disclosed may be made within the scope of what is claimed without departing from the spirit of my invention.

75

I claim:

1. A humidifying device comprising a rectangular case having an opening near one end thereof, a nozzle in said case for directing a spray of water along said case, a drain 80 in the said case for removing the surplus water therefrom, and a partition within said case extending between two of the walls thereof and being spaced from the other walls and falling short from the end of said case in which said drain is situated, said partition being removable through the opening.

2. A humidifying device comprising a rectangular case having an opening near one end thereof, a nozzle in said case, a curved 90 deflector extending between the side walls of said case and attached to the front wall within and immediately above said opening, a removable partition insertible through said opening adapted to be supported within said case with one of its edges in contact with said curved deflector, wing-like portions formed on said partition and a second deflector mounted between said wing-like portions being disposed in spaced relation to said first 100 deflector and to said partition, and being removable with said partition through said opening.

3. A humidifying device comprising a case having a discharge outlet, means within said case for humidifying the air passing through said outlet, a drain in said case near said outlet for removing the surplus water from said case, a partition in said case positioned in proximity to said drain and forming with said case a passageway leading up to said outlet, said partition being removable through said outlet to give access to said drain through said outlet.

4. A humidifying device comprising a rectangular case having an opening in the front wall thereof above the bottom of said case, means within said case for humidifying the air passing through said case, a drain in the bottom of said case for removing surplus water therefrom, guideways formed along the side walls of said case, a removable partition insertible through said opening adapted to be slid along said guideways, and a stop for limiting the movement of said partition 115 along said guideways.

5. A humidifying device comprising a case having an outlet, means within said case for humidifying the air passing through said outlet, a removable partition within said case 130

positioned in proximity to said outlet, said partition being removable through said outlet and a deflector within said case extending from said partition to said case and being a continuation of said partition, said partition and deflector forming with said case a passageway leading up to said outlet.

5 6. A humidifying device comprising a case having an outlet, means within said case for 10 humidifying the air passing through said outlet, a removable partition within said case positioned in proximity to said outlet, said partition being removable through said outlet and a deflector within said case extending 15 from said partition to said case and being a continuation of said partition, said partition and deflector forming with said case a passageway leading up to said outlet, and a second deflector attached to said partition and 20 spaced from said partition and first deflector, said second deflector being removable with said partition through said outlet.

7. A humidifying device comprising a case having a discharge outlet, means within said 25 case for humidifying the air passing through said outlet, a removable partition in said case disposed adjacent said outlet and forming with said case a tortuous passageway communicating with said outlet, said partition 30 being removable through said outlet to eliminate said tortuous passageway, and a support within said case for holding said partition in operative position therein.

In testimony whereof, I have signed my
35 name to this specification.

DANIEL HANDELAN.
